UNITED STATES PATENT OFFICE.

THOMAS HENRY MARTEN, OF TORONTO, ONTARIO, CANADA.

ATTACHMENT FOR LIFE-BOAT DAVITS.

1,319,352.

Specification of Letters Patent. Patented Oct. 21, 1919.

Application filed March 5, 1918. Serial No. 220,515.

To all whom it may concern:

Be it known that I, THOMAS HENRY MARTEN, a subject of the King of Great Britain, and resident of the city of Toronto, county 5 of York, Province of Ontario, in the Dominion of Canada, have invented certain new and useful Improvements in Attachments for Life-Boat Davits, described in the following specification and illustrated in the 10 accompanying drawings, that form part of the same.

The principal object of this invention is to provide improved means for minimizing the power required for moving ships' boats 15 from their overhung or lowering position to their inboard, or stowed position and vice versa and especially for use with a davit of the type in which the boom swings upon a fixed pivot in a vertical plane.

20 It is well understood by those skilled in the handling of ships' boats with the type of davit referred to, that one of the greatest difficulties met with is the excessive work required in raising the load in addition to 25 that required to displace it transversely due to the path of travel of the boom head from which the boat is suspended. This is more particularly the case when the boat is being moved back from its overhung position.

30 In the operation of the type of davit pivoted at the foot if the path of travel of the load corresponded with the path of travel of the boom head there would be an objectionable tendency for the load to run 35 forward when being moved toward the overhung position and it is therefore desirable to effect as nearly as possible a horizontal path of travel for the load so that the davit and its load will in all positions be in a 40 condition of approximate equilibrium and so that the only work involved will be that required to displace the load transversely.

The principal feature of the invention consists in the novel construction and arrangement of parts whereby the davit boom when swinging outwardly and downwardly from the vertical line of support of the load is accompanied by a reactionary pull upon the tackle ropes which causes the boat 50 to be held to a more nearly horizontal path than that described by the boom head.

In the accompanying drawings Figure 1 is an elevational view showing my improved form of davit attachment and illustrating 55 its application to a davit and a boat and showing the character of the path of travel

of the boat as compared with that of the davit boom head, the extreme outboard position being shown in dotted lines.

Fig. 2 is an elevational view showing the 60 position of the members when the boom head is located in the vertical line of the support of the load that is, in vertical alignment with the pivot support of the boom.

In practically all the present forms of 65 mechanically operated davits in which the boom swings in a vertical plane the major portions of the path of movement of the boat outboard is in a downward direction due to the pivoting of the boom and the 70 consequent downward movement of the boom head as it swings to an outboard or overhung position.

It is the purpose of this invention to obviate this condition by effecting a positive 75 reactionary movement to draw upon the tackle ropes as the boom head swings downwardly thus causing the boat to travel in a plane substantially parallel to the ship's deck.

In carrying my invention into effect I preferably utilize a solid cast frame 1 which is rigidly secured to the deck of the ship at the rail having the outer upright 2 and inner post 3 connected adjacent to the top 80 by the cross piece 4 cast as part of the frame.

The crosshead bar 5 is secured in the upper end of the upright 2 and post 3 and is preferably parallel to the piece 4 which is arranged with an upward and outward incline.

The boom 6 is preferably bifurcated at the lower end and straddles the frame and crosshead bar and is pivoted at its foot upon the pivot pin 7 which is arranged at the base of 95 the upright 2.

The profile of the boom is preferably of obtuse angular or curved formation so that when the upper portion of the boom is in an upright position the lower end extends 100 diagonally across the frame from the lower front to the rear upper portion, and so that when the davit is in its normal inboard position the boom head from which the load is suspended is inboard of the pivotal support of the boom.

A crosshead 8 is slidably arranged on the crosshead bar 5 and provided with a pair of downwardly extending lugs 9.

A threaded spindle 10 is journaled in suitable bearings in the upper ends of the upright 2 and post 3 and is arranged im-

mediately below and parallel with the crosshead bar 5 and extends through the lugs 9 on the crosshead.

A floating nut 11 is threaded on the 5 spindle and held between the lugs 9 and forms the means for effecting the travel of the crosshead. The crosshead is formed with a bearing lug 12 on its upper and rearward end and in this lug is secured the link pin 13.

10 A link 14 formed with a bifurcated end 15 straddling the lug 12 is secured upon the link pin 13 and the other end extends through the bifurcated portion of the boom and is pivotally connected to the pin 15' secured in the forward side of the said boom.

15 The rotation of the spindle travels the crosshead 8 upon the crosshead bar 5 and through the link 14 swings the boom on its pivot.

20 A crank lever 16 is pivotally mounted upon a rigid pivot pin 17 secured in the frame adjacent to the inner side, said lever having the long end 18 extending in an upward and inboard direction and provided

25 with a cleat 19 at its inner end to which the tackle rope is secured. The short cranked end 20 of the lever 16 extends in an outboard direction and pivotally secured to the outer end thereof is a shackle rod 21. The other 30 end of the shackle rod 21 is pivotally secured to one end of the link pin 13 of the crosshead 8.

35 The operation of this shackle and lever is governed directly by the movement of the crosshead and is therefore operative relative to the boom. As the crosshead moves from its normal position in an outboard direction the shackle rod 21 acting as a tie permits the short end of the lever 16 to swing downwardly upon its pivot and allowing the long end 18 to swing upwardly and forwardly in

40 response to the tension in the tackle ropes as the boom takes the weight of the boat. The upward and forward swinging movement of the long end of the lever is gradually decreased as the shackle rod approaches the position perpendicular to the line of travel of the crosshead until the forward movement of the long end of the lever ceases as

45 illustrated in Fig. 2. The continued forward movement of the crosshead thus reverses the action of the lever 16 and the crosshead then pulls upwardly upon the shackle rod 21 and short end 20 of the lever 50 causing the long end 18 to swing in an inboard rearward direction.

55 The path of movement of the lever is shown in the drawings by a dotted line and the limit of the outboard movement is indicated by α . The boat is suspended from the upper end of the boom by the tackle ropes 22 and the working part of the rope is secured to the cleat 19 on the long end of the lever 16. The boom 6 is pivoted at its foot and 60 normally rests with its upper end inboard

of the center of gravity and upon the operation of the screw spindle 10 by means of the crank 23 the boom is swung outwardly. It has a considerable lifting action, that is to say, the boom head first travels in an ascending arc which lifts upwardly upon the tackle ropes and lifts the boat clear of the chocks. 70

75 The lifting action due to the path of movement of the boom head is desired at the beginning of the movement of the boom so that all slack and stretch may be thus taken out of the tackle ropes and the boat lifted off the chocks but it is found that the lifting action of the boom is sufficient for this 80 purpose and it is therefore objectionable to have the tackle ropes pull through the blocks when the davit is first put in motion. By attaching the working part of the tackle rope to the lever 16 this objection is overcome during the first part of the movement of the boom by the concurrent forward movement in the lever 16. This movement is gradually decreased until the shackle rod 21 passes over the dead center and a reactionary movement in the lever 16 then takes place and as the boom continues to move outboard, the lever 16 swings inboard. This reactionary movement draws upon the tackle ropes and causes the boat to be carried in a substantially horizontal path, the reactionary movement of the lever drawing upon the ropes in substantial proportion to the depression of the boom head in the outboard portion of its travel. The path of 90 movement of the boat is shown by the line α and is a flat arc having its chord substantially parallel to the deck of the ship. 95

100 From this description and on reference to the diagrams it will be seen that the boat may be lifted clear of the chocks and carried free of the rail of the ship by the ascending arc of the boom head and is further prevented by the reactionary means shown, from dropping away as the boom swings 110 outboard and downward to its maximum position with the result that a minimum of effort is required to displace the load from one position to another. 115

120 I find the form of davit shown convenient to illustrate the application of my invention but it must be understood that it may be attached to other forms of davits to operate effectively.

What I claim as my invention is:—

1. In a davit attachment, the combination with the davit frame and boom, of means arranged upon the frame and adapted to be operated by the boom and through the operation of the boom to effect a reactionary pull upon the tackle ropes supporting the boat as the boom head swings outwardly and downwardly. 125

2. In a davit attachment, the combination with the davit frame and boom, of a lever 130

member pivoted on the frame and connected to the tackle ropes supporting the boat, and means connecting said lever with said boom to effect the movement of said lever in a direction opposite to that of the boom as the boom head moves outboard of the perpendicular line of support of the load.

3. In a davit attachment, the combination with the davit frame and boom, of a lever member pivoted on the frame intermediate of its length having one end secured to the tackle ropes supporting the boat, a shackle rod connecting the opposite end of said lever with the boom and adapted 15 to swing said lever in a direction opposite to the movement of the boom as the boom swings outboard of the perpendicular line of support of the load.

4. In a davit attachment, the combination 20 with the davit frame and boom, of a lever

member pivoted on the frame intermediate of its length having one end secured to the tackle ropes supporting the boat, means for operating the boom, and a shackle rod pivotally connected at one end to said boom 25 operating means and at the other end to said lever to effect the operation of said lever in a direction opposed to the movement of the boom outboard of the perpendicular line of support of the load.

5. In a davit attachment, the combination with the davit frame and boom, of a lever pivoted on the frame and having one end connected to the ropes for supporting the boat, and a shackle rod connecting the other 35 end of said lever with the boom to effect a reversal of the movement of said lever at a point intermediate of the movement of the boom.

THOMAS HENRY MARTEN.
